PAGE-END INDICATING DEVICE

Martin M. Price, Orange, N. J.

Application March 23, 1932. Serial No. 600,596

16 Claims. (Cl. 197—189)

My present invention relates to indicators, and more particularly to devices of the general character specified which may be used in conjunction with typewriting machines and which are adapted to warn the operator of the approach of the end or bottom of a page.

It is one of the main objects of the present invention to provide what may be termed a page-end indicator which is exceedingly simple in construction, easy and economical to fabricate and assemble, and which performs the intended functions in an admirable manner.

I am aware of the fact that page-end indicators are not broadly new, but I have found that they are for the most part cumbersome, complicated and therefore expensive. Furthermore, all of the page-end indicators of which I am aware are designed to constitute an integral part of the typewriter, whereas the present invention is intended to be an attachment which may be very readily and speedily secured to any existing typewriter.

It may here be stated that my present invention constitutes an improvement over the one described and claimed in my co-pending application, entitled "Page-end indicators", Serial No. 592,035, filed February 10, 1932.

In the accompanying specification I shall describe, and in the annexed drawing show, an illustrative embodiment of the page-end indicators of the present invention. It is, however, to be clearly understood that I do not wish to be limited to the exact construction herein shown and described for purposes of illustration only.

In the accompanying drawing:

Fig. 1 is a fragmentary top plan view of a conventional typewriter equipped with the aforesaid illustrative embodiment of the present invention;

Fig. 2 is a partially transverse sectional, par-

tially side elevational view of the same;

Fig. 3 is a longitudinal sectional view taken substantially through the center of the plunger arrangement used as part of the aforesaid illustrative embodiment of the present invention; and

Fig. 4 is a rear plan view showing the relationship of a sheet of paper to be written upon to a backing sheet adapted to be used in conjunction with the aforesaid illustrative embodiment of the present invention.

Referring now more in detail to the aforesaid illustrative embodiment of the page-end indicating devices of the present invention, and with particular reference to the drawing illustrating the same, the numeral 10 generally designates

55 the carriage of a conventional typewriter, which

carriage carries the platen or roller 11 with which cooperates paper guides 12, the platen and paper guides being adapted to accommodate between the same a sheet of paper P.

Secured to any desired part of the carriage 10, 60 such as the transverse bar 13, is a mounting member 14 consisting of the straddling elements 15 adapted to engage the bar 13 and be securely affixed thereto by means of an adjusting screw 16, and an upper socket portion 17.

The socket portion 17 is receptive of a short bar 18 adapted to lie in a plane parallel with the plane of the sheet of paper P when in position to be written upon.

Adjustable along the length of the bar 18 is an 70 oversized socket 19, the same being adjustable in its position along the length of the bar 18 by means of the thumb screw 20.

Integrally formed with the oversized socket 19 is a web portion 21 which in turn has integrally 75 formed therewith a cylinder 22. The cylinder 22 is provided at the open ends thereof with apertured bushings 23 and 24, upper and lower, respectively, the bushings being adapted to guide a plunger 25 which is reciprocably mounted in 80 the cylinder 22 and which is provided, at a right angle thereto, with a tripping member 26 extending outwardly from the cylinder 22 through a longitudinal slot 27. The plunger 25 is normally maintained in an upper position, as clearly 85 shown in Fig. 3 of the drawing, by means of an expansion spring 28, the lower end of which is adapted to abut the lower bushing 24, and the upper end of which is adapted to abut the tripping member 26.

The tripping member 26 includes a pair of spaced resilient arms 29 and 30 presenting a space 31 therebetween, the space being adjustable in size by means of the set screw 32 engageable in the arms 29 and 30. The outer ends of 95 the arms 29 and 30 are bevelled, as at 33, so as to present a guiding entrance to the space 31, the purpose of which will later become apparent.

The upper end 34 of the plunger 25 constitutes an alarm-engaging element which is adapted to 100 cooperate with a bell 35 fixed upon a post 36 carried by an offset portion 37 of the cylinder 22, the bell engaging portion 34 of the plunger being normally maintained slightly spaced away from the bell 35 by means of a small expansion 105 spring 38.

This completes the description of the aforesaid illustrative embodiment of the present invention and though the operation thereof is thought to clearly appear from such foregoing 110

description, it is desired, for the sake of clarity, to briefly summarize the same as follows:

- In use, the devices of the present invention are preferably fixed upon the left side of the carriage 5 of the typewriter. Before placing the sheet of paper P in the machine to be written upon, it is superimposed upon a backing sheet 39 in such a manner that the lower edge P' of the sheet of paper P coincides with the lower edge 39' of the 10 backing sheet 39. The backing sheet is provided in the upper left hand corner thereof with a tab 39'', the purpose of which will become apparent as the description of the mode of operation and use progresses.
- 15 The backing sheet, together with the sheet of paper to be written upon, is now placed in the machine in the usual manner, the same being guided about the platen 11 by the guiding rollers 12. The backing sheet 39 is furthermore engaged 20 in the space 31 intermediate the arms 29 and 30 of the tripping member 26 and, of course, being of lesser thickness than the width of the slot 31, is loosely engaged therein.
- 25 The device is now ready for use and the typist 25 proceeds to operate the machine in the usual manner. As the sheet of paper P, together with the backing sheet 39, passes through the machine, the tab 39'' approaches the tripping member 26. As soon as the tab 39'' comes into contact with the tripping member 26, being of slightly greater thickness than the width of the space 31, the tab 39'' becomes wedged intermediate the arms 29 and 30. Continued passing of the sheet of paper P, together with the backing sheet 39, 30 through the machine causes the tripping member and the plunger to which it is secured to follow downwardly after the paper. Obviously, as soon as the tripping member 26 comes into contact with the lower bushing 24, it cannot move any further, so that any additional movement of the paper P, together with the backing sheet 39, will meet with such resistance, that the wedged tab 39'' of the backing sheet will pass 35 through the slot 31, thus disengaging the arms 29 and 30. As soon as the tripping member is released, the expansion spring 28 will cause the plunger 25 to immediately return to its normal position, the momentum of the upward movement being such as to cause the alarm-engaging end 34 of the plunger to strike the bell 35, thus 40 warning the operator that he has reached such a point on the sheet of paper P as to throw the typed sheet out of balance if any additional matter is written thereupon.
- 45 It will be noted that the point at which the bell will be operated may be varied by adjusting the socket 19 along the length of the bar 18, so that the operator can be warned of the fact that he has reached a certain point on the paper at any distance from the end of the page that he desires. It will further be noted that the arms 29 and 30 can be adjusted so as to vary the space 31, thus permitting the use of the devices of the 50 present invention in conjunction with more than one thickness of paper.

This completes the description of the mode of operation and use of the page-end indicating devices of the present invention, and it will be noted that such page-end indicating devices are exceedingly simple in construction, very easy and economical to fabricate and assemble, and admirably adapted to perform the intended functions as hereinbefore set forth.

70 Other superiorities and advantages of the devices of the present invention will readily occur

to those skilled in the art to which the present invention relates.

What I claim as my invention is:

1. An attachment for typewriters comprising a support, a casing adjustable along said support, 80 an audible signal, spring-pressed signal-operating means carried by said casing, tripping mechanism carried by said casing, a pair of spaced resilient arms carried by said signal-operating means, and means, cooperating with said tripping mechanism and a sheet of paper to be typed upon, to engage and thereafter release said tripping mechanism when the sheet of paper has passed a predetermined distance through the typewriter, to operate said audible signal.
2. An attachment for typewriters comprising 90 a support, a casing adjustable along said support, an audible signal, signal-operating means carried by said casing, a pair of spaced resilient arms carried by said signal-operating means, and means, cooperating with said pair of spaced resilient arms and a sheet of paper to be typed upon, to engage and thereafter release said pair of spaced resilient arms when the sheet of paper has passed a predetermined distance through the typewriter, to operate said audible signal.
- 20 95 3. An attachment for typewriters comprising a support, a casing adjustable along said support, an audible signal, signal-operating means carried by said casing, a pair of adjustably spaced resilient arms carried by said signal-operating 105 means, and means, cooperating with said pair of adjustably spaced resilient arms and a sheet of paper to be typed upon, to engage and thereafter release said pair of adjustably spaced resilient arms when the sheet of paper has passed 110 a predetermined distance through the typewriter, to operate said audible signal.
4. An attachment for typewriters comprising a support, a casing adjustable along said support, an audible signal, spring-pressed signal-operat- 115 ing means carried by said casing, a pair of spaced resilient arms carried by said spring-pressed signal-operating means, and means, co- 120 operating with said pair of spaced resilient arms and a sheet of paper to be typed upon, to engage and thereafter release said pair of spaced resilient arms when the sheet of paper has passed a predetermined distance through the typewriter, to operate said audible signal.
5. An attachment for typewriters comprising 125 a support, a casing adjustable along said support, an audible signal, spring-pressed signal-operating means carried by said casing, a pair of 130 adjustably spaced resilient arms carried by said spring-pressed signal-operating means, and means, 135 cooperating with said pair of adjustably spaced resilient arms and a sheet of paper to be typed upon, to engage and thereafter release said pair of adjustably spaced resilient arms when the sheet of paper has passed a predetermined distance through the typewriter, to operate said audible signal.
6. An attachment for typewriters comprising 140 a support, a casing adjustable along said support, an audible signal, signal-operating means carried by said casing, tripping mechanism carried by said signal-operating means, and means, 145 cooperating with said tripping mechanism and a sheet of paper to be typed upon, to engage and thereafter release said tripping mechanism when the sheet of paper has passed a predetermined distance through the typewriter, to operate said audible signal, said last-named means including a backing sheet provided with a tab cooperable with said tripping mechanism.
- 150

7. An attachment for typewriters comprising a support, a casing adjustable along said support, an audible signal, spring-pressed signal-operating means carried by said casing, tripping mechanism carried by said spring-pressed signal-operating means, and means, cooperating with said tripping mechanism and a sheet of paper to be typed upon, to engage and thereafter release said tripping mechanism when the sheet of paper has passed a predetermined distance through the typewriter, to operate said audible signal, said last-named means including a backing sheet provided with a tab cooperable with said tripping mechanism. 80
15. An attachment for typewriters comprising a support, a casing adjustable along said support, an audible signal, signal-operating means carried by said casing, a pair of spaced resilient arms carried by said signal-operating means, and means, cooperating with said pair of spaced resilient arms and a sheet of paper to be typed upon, to engage and thereafter release said pair of spaced resilient arms when the sheet of paper has passed a predetermined distance through the typewriter, to operate said audible signal, said last-named means including a backing sheet provided with a tab cooperable with said pair of spaced resilient arms. 85
9. An attachment for typewriters comprising a support, a casing adjustable along said support, an audible signal, signal-operating means carried by said casing, a pair of adjustably spaced resilient arms carried by said signal-operating means, and means, cooperating with said pair of adjustably spaced resilient arms and a sheet of paper to be typed upon, to engage and thereafter release said pair of adjustably spaced resilient arms when the sheet of paper has passed a predetermined distance through the typewriter, to operate said audible signal, said last-named means including a backing sheet provided with a tab cooperable with said pair of adjustably spaced resilient arms. 90
10. An attachment for typewriters comprising a support, a casing adjustable along said support, an audible signal, spring-pressed signal-operating means carried by said casing, a pair of spaced resilient arms carried by said spring-pressed signal-operating means, and means, cooperating with said pair of spaced resilient arms and a sheet of paper to be typed upon, to engage and thereafter release said pair of spaced resilient arms when the sheet of paper has passed a predetermined distance through the typewriter, to operate said audible signal, said last-named means including a backing sheet provided with a tab cooperable with said pair of spaced resilient arms. 95
11. An attachment for typewriters comprising a support, a casing adjustable along said support, an audible signal, spring-pressed signal-operating means carried by said casing, a pair of adjustably spaced resilient arms carried by said spring-pressed signal-operating means, and means, cooperating with said pair of adjustably spaced resilient arms and a sheet of paper to be typed upon, to engage and thereafter release said pair of adjustably spaced resilient arms when the sheet of paper has passed a predetermined distance through the typewriter, to operate said audible signal, said last-named means including a backing sheet provided with a tab cooperable with said pair of adjustably spaced resilient arms. 100
12. An attachment for typewriters comprising a support, a cylinder adjustable along said support, an audible signal, a signal-operating plunger carried by said cylinder, tripping mechanism carried by said signal-operating plunger, and means, cooperating with said tripping mechanism and a sheet of paper to be typed upon, to engage and thereafter release said tripping mechanism when the sheet of paper has passed a predetermined distance through the typewriter, to operate said audible signal. 105
13. An attachment for typewriters comprising a support, a cylinder adjustable along said support, an audible signal, a spring-pressed signal-operating plunger carried by said cylinder, a pair of adjustably spaced resilient arms carried by said spring-pressed signal-operating plunger, and means, cooperating with said pair of adjustably spaced resilient arms and a sheet of paper to be typed upon, to engage and thereafter release said pair of adjustably spaced resilient arms when the sheet of paper has passed a predetermined distance through the typewriter, to operate said audible signal. 110
14. An attachment for typewriters comprising a support, a cylinder adjustable along said support, an audible signal, a signal-operating plunger carried by said cylinder, tripping mechanism carried by said signal-operating plunger, and means, cooperating with said tripping mechanism and a sheet of paper to be typed upon, to engage and thereafter release said tripping mechanism when the sheet of paper has passed a predetermined distance through the typewriter, to operate said audible signal, said last-named means including a backing sheet provided with a tab cooperable with said tripping mechanism. 115
15. An attachment for typewriters comprising a support, a cylinder adjustable along said support, an audible signal, a spring-pressed signal-operating plunger carried by said cylinder, a pair of adjustably spaced resilient arms carried by said spring-pressed signal-operating plunger, and means, cooperating with said pair of adjustably spaced resilient arms and a sheet of paper to be typed upon, to engage and thereafter release said pair of adjustably spaced resilient arms when the sheet of paper has passed a predetermined distance through the typewriter, to operate said audible signal, said last-named means including a backing sheet provided with a tab cooperable with said pair of adjustably spaced resilient arms. 120
16. An attachment for typewriters comprising a support, a casing adjustable along said support, an audible signal, signal-operating means carried by said casing, tripping mechanism carried by said signal-operating means, and means, cooperating with said tripping mechanism and a sheet of paper to be typed upon, to engage and thereafter release said tripping mechanism when the sheet of paper has passed a predetermined distance through the typewriter, to operate said audible signal. 125

MARTIN M. PRICE.
